SUCTION CLEANER

Paul E. Frantz, Euclid, Ohio, assignor to The
Apex Electrical Manufacturing Company,
Cleveland, Ohio, a corporation of Ohio

Application November 6, 1940, Serial No. 364,529

4 Claims. (Cl. 15—16)

This invention relates to suction cleaners and more particularly to a portable, electric suction cleaner suited for the cleaning of floors, rugs and the like.

It is among the objects of my invention to provide a suction cleaner having a nozzle adapted to engage a floor, rugs or the like, a motor and fan unit cooperating with the nozzle to effect a cleaning action therethrough, and a dust bag to hold the dust and litter removed from the surface undergoing cleaning, constructed and arranged so that the air stream which effects cleaning is directed toward the dust bag through a passageway formed in part by the motor so as to effect a cooling of the motor.

It is a further object of my invention to provide a suction cleaner according to the preceding object, which comprises a body having an integrally formed nozzle and shell and wherein the fan and motor as a unit are proportioned and arranged so that the shell functions as a fan chamber, a motor housing and an air passageway to conduct the air from the nozzle to the dust bag.

It is a further object of my invention to provide a suction cleaner according to the preceding object, wherein the nozzle is provided with an adjustable rotary brush fitted with removable brush elements and is adapted to be driven from the motor shaft.

It is a further object of my invention to provide a suction cleaner having a nozzle wherein the top and forward walls thereof are shaped to provide a reentrant portion to support and protect an illuminating device for the cleaner.

It is a further object of my invention to provide a suction cleaner having a rotary brush, wherein the brush comprises semi-cylindrical shell members mounted on a core and which are shaped and arranged to receive and hold a removable brush element.

It is a further object of my invention to provide a suction cleaner body having a handle pivotally carried by a bracket thereon and which is provided with a latch adapted to cooperate with portions of the bracket and wherein spring means are provided to counterbalance the weight of the handle.

It is a further object of my invention to provide a suction cleaner having a nozzle with front and rear supporting wheels proportioned with respect to each other to effect automatic adjustment of the nozzle.

Further objects and advantages relating to efficiency in operation and economies in manufac-

ture will appear from the following description and the appended drawings, wherein:

Figure 1 is a sectional view taken longitudinally of the suction cleaner;

5 Figure 2 is a plan view with parts in section of a cleaner made according to my invention;

Figure 3 is a plan view with parts in section of a motor and fan unit embodied in the cleaner;

10 Figure 4 is a sectional view of the motor showing ventilation and motor brush details;

Figure 5 is an end view with parts broken away showing the motor brush mounting;

Figure 6 is a front elevation with parts in section showing the rotating brush mounted in the 15 cleaner nozzle;

Figure 7 is a sectional view showing the brush construction;

Figure 8 is a sectional view taken as indicated at 8—8 of Figure 6;

20 Figure 9 is a sectional view taken as indicated at 9—9 of Figure 6;

Figure 10 is an elevation with parts in section of a suction cleaner handle made according to my invention;

25 Figure 11 is an enlarged sectional view of the handle latch mechanism; and

Figure 12 is an enlarged view with parts broken away of the handle latch mechanism.

The cleaner of my invention comprises a body 30 provided with wheels adapted to support the cleaner for movement over a rug or surface to be cleaned, a nozzle provided with a rotary brush and a fan and motor chamber in communication with the nozzle providing a passageway leading to a dust bag.

35 In portable suction cleaners it has been the general practice to separate the motor unit from the fan chamber so as to prevent dirt-laden air from contact with the motor. It has been recognized that the large volume of air moved by the

40 fan might be utilized to assist in the cooling of the motor and thus permit a more efficient use of the materials employed in constructing the motor. It has also been recognized that the cooling effect on the exterior of the motor casing should be supplemented by the introduction into the motor casing of clean air from the exterior of the cleaner. Numerous attempts heretofore made, however, to mount the motor in the air stream of the suction cleaner have resulted in 45 expensive and inefficient arrangements and in constructions which adversely affected the cooling and ventilating of the motor.

Generally speaking, I have obtained the advantages above mentioned by providing a cleaner

body with an elongated shell which serves to conduct the air from the nozzle to the dust bag and which is provided with an apertured portion at the lower side of the shell adapted to receive and support a motor similarly apertured so that ventilating air may be drawn from the exterior of the shell into a motor casing and exhausted through said apertures.

Referring to the drawings, the cleaner body indicated in its entirety as at 1 comprises three complementary castings 2, 3 and 4. The casting 3 is provided with supporting wheels 5 and 6 beneath the forward portion of the casting and wheels 7 and 8 at the rear portion of the casting. The casting indicated at 2 is in the nature of a cover for the lower casting and is shaped to provide therewith an elongated shell which forms a conduit for the air stream leading from the nozzle to the dust bag, a fan chamber, and a motor housing. The casting 3 in its forward portion is shaped to provide a floor nozzle 3a extending transversely of the cleaner and the upper portion of this nozzle at the central part thereof is covered by a portion of the casting 4. An extension of the casting 4 overhangs a recess or ledge in the upper surface of the nozzle to provide a cover or guard for the light 9. The casting 4 is removably mounted on castings 2 and 3 by means of the spring clip 130 secured to the lower edge of the extension of the casting 4 which engages a knob 131 carried by the nozzle portion 3a and spring clip 132 which engages a projection 133 on the casting 2.

Preferably the end walls of the nozzle are continued rearwardly as at 3b so as to provide a housing concealing the supporting wheels 5 and 6 and thus contribute to the stream-lined shape and general attractiveness of the cleaner. The forward supporting wheels 5 and 6 have relatively wide floor-contacting surfaces and have a relatively greater diameter than the rear wheels 7 and 8. The wide, large diameter wheels 5 and 6, permit the cleaner to ride easily on a soft or deep-pile rug, without sinking into the rug sufficiently to adversely affect the efficient cleaning of the rug by the nozzle. In this connection it is pointed out that the narrow wheels 7 and 8 at the rear of the cleaner permit that portion of the cleaner to sink farther into the rug than the front portion of the cleaner and thus the proper efficient space between the nozzle and the surface to be cleaned is automatically maintained. The castings 2, 3 and 4 are free of reentrant portions and are thus suited for low cost production by the use of die castings.

The lower wall of the casting 3 which forms the shell enclosing the motor and fan unit is shaped to provide a flat boss or motor support section 11 which is apertured as at 12 and 13 for ventilating inlet and outlet, respectively. The section 11 as shown in plan in Figure 2 is substantially triangular in shape and corresponds to the shape of the boss 15 formed on the base of the motor casing 75. The boss 15 of the motor casing 75 is likewise apertured as at 12a and 13a to provide ventilating air inlet and outlet respectively in the motor casing. A resilient gasket 16 is inserted between the motor boss 15 and the section 11 to effectively seal the motor ventilation openings with respect to the air stream within the cleaner shell and to deaden sound and vibration resulting from motor operation. The motor is secured in position on the casing section 11 by suitable fastening screws 17.

The above described mounting arrangement 75

for the motor and fan unit within a shell provides for a free passage of air about the exterior of the motor casing 75 except in the supporting section 11 at the lower part of the casing, and the motor boss 15 is so proportioned that the motor and fan unit is substantially centrally disposed within the casing. The positioning of the motor and fan with respect to the inlet 20 in the nozzle end of the shell and the shaping of the fan and shell as shown, results in a quiet unit of high efficiency. The efficiency obtained appears to be due at least in part to the fact that the air drawn from the nozzle is directed longitudinally in a substantially straight line as it leaves the fan through a large passageway as distinguished from the conventional motor and fan unit arrangement, wherein a fan chamber is provided with an outlet at one point and the air follows a restricted, tortuous passage producing turbulence and noise.

I have found that by mounting the motor against the lower wall, so as to prevent the passage of air between the under side of the motor and the casing, it prevents any swirling action in the air stream through the casing and it appears that the elimination of this swirling action also contributes to the quietness and high efficiency obtained. The spacing between the exterior of the motor casing and the air stream casing is preferably such that the cross sectional area through this passage is not less than the cross sectional area in other portions of the air stream passageway and thus there is no restriction to free air flow through the casing.

35 The cleaner castings 2 and 3 which form the shell housing the motor and fan, terminate in a dust bag opening at the rear of the cleaner and a ring 55 which is carried by and forms the mouth of the dust bag, is secured to the casting 3 by thumb nuts 56-57 on studs carried by casting 3. The fabric of the dust bag is suitably secured to a reentrant groove of the ring 55 by a clamping band 59 carried in the hem of the dust bag. By removing the thumb nuts 56-57, the 45 dust bag, in its entirety may be removed from the cleaner and emptied.

40 A pulley 21 is secured to the motor shaft 22 forwardly of the fan 23 and the pulley projects through the casing opening 20 to provide a drive 50 through the belt 24 to the brush unit 25 mounted in the lower part of the nozzle. As shown in Figure 6, the floor nozzle 3a extends transversely of the cleaner and the end walls thereof are provided with brackets 27 and 28 to support the 55 rotatable brush. The brackets 27-28 are vertically slotted as at 29 (see Fig. 8) to receive a pin 33 carried by the end of the rotatable brush to permit proper brush adjustment within the nozzle. Preferably the pin 33 has flat sides so as to be restrained against rotation and guided 60 vertically by the edges of slot 29. A slotted plate 30 is pivoted as at 31 on the supporting plate 27 and the slot 32 in the plate 30 is curved so that rocking movement of the plate 30 raises 65 and lowers the pin 33. The swinging or adjusting movement of the plate 30 is effected by manually moving the handle portion 34 and said movement is controlled by a spring-pressed latch 35 adapted to be received in notches 36 formed in 70 the lower edge of the plate 30. It will be understood that the tension of the belt 24 normally pulls the brush upwardly in the slot 29 so as to cause the pin 33 of the brush to bear against the upper edge of the cam slot 32.

The brush unit 25 comprises a hollow tube 38

having a belt pulley 39 secured to the central portion thereof and a bearing member 40 carried at each end thereof. To support the brush for rotation, a reduced shank portion 33a of the pin 33 extends into the bore formed in the bearing member 40. Semi-cylindrical metal shell members 41 are mounted on the tube 38 and secured thereto by screws 42 and said shells 41 are preferably spiraled and spaced slightly from each other to provide a reentrant groove to receive spiral brush elements 43. The ends of the spiral shells adjacent the pulley 39 extend beneath a collar or ring 44 secured to the belt pulley and the other end of the shells are flanged as at 45 beneath a collar or ring 46 which is attached to the flanged portion by screws or the like 47. Preferably the brush elements 43 have the end portions thereof projecting beneath the members 44 and 46 to prevent outward radial movement in response to centrifugal force during rotation. A disk or washer 48 is integrally formed or secured to the pin 33 and is proportioned to overhang the collar 46 as shown.

The above-described brush construction provides that the brush elements 43 may be replaced when worn by removing the screws 47, the collar 46 and sliding the brush element 43 longitudinally of its groove.

The open mouth of the suction nozzle 3a is partially closed by a plate 50 which is apertured as at 51 in the area opposite the brush bristles. The plate thus provided prevents a rug or the like undergoing cleaning from being drawn too far into the suction mouth and thus properly positions such rug for cleaning by the rotating brush and the suction action through the openings 51.

The motor and fan unit as shown in Figures 3 to 5 comprises a motor casing, indicated in its entirety as at 15 and includes a frame 16, a forward end bell 17 and rearward end bell or cap 18. The frame 16 supports by means of longitudinally extending screws 80a, a stator 80 which surrounds the rotor 19 fixed to the motor shaft 22. The forward end of the motor shaft is suitably mounted in anti-friction bearings 88 carried by the forward end bell 17 and the rearward end of the motor shaft is supported in a bearing 83 carried by a bearing support member 82 integrally cast or formed with the frame 16. The cap or end bell 18 is preferably formed of Bakelite or similar molded material and is shaped to conform to the stream-lined contour of the frame 16. The cap 18 may be removed to facilitate replacement or adjustment of the carbon brushes arranged to bear against the commutator 81 of the rotor. A baffle 86 is secured to the stator by the screws 80a and is apertured centrally thereof as at 87 to provide an air inlet to the fan 85 carried by the motor shaft 22 within the motor casing. Upon operation of the motor, ventilating air will be drawn by the fan 85 upwardly through the aperture 12a at the lower side of the motor, thence through the rear end portion of the motor and about the carbon brushes, thence longitudinally through the motor to the opening 87 in the baffle 86. The air is exhausted from the motor casing by the fan 85 through the opening 13a also formed in the lower side of the motor casing.

The above-described arrangement insures that a quantity of cooling, ventilating air will be drawn from the exterior of the cleanser through the motor and then exhausted beneath the cleaner. The forward end bell 17 and the rear end bell or cap 18 are tightly secured to the

main frame 16 so as to exclude from the motor casing any dust-laden air which is being moved from the nozzle to the dust bag.

Carbon brushes 90 and 91 are horizontally arranged so as to bear against the commutator 81 at the rear end of the rotor. The brushes are slidably mounted in a rectangular casing 92, carried on the plate 93, which plate is formed of insulating material and is secured by screws 94 to lugs 95 integrally formed with the main frame 16. The brushes are slotted and notched at their outer ends to receive a lug 96 carried by a lobe 97. To resiliently urge the brush members 90 and 91 toward each other, the outer ends of yokes 97 are connected to each other by coil springs 98. The above-described brush arrangement provides that equal spring pressure is applied to both of the brushes at all times and further provides an efficient compact arrangement that may be housed within the cap 18.

It will be understood that the employment of the conventional brush arrangement wherein coil springs are arranged axially on each brush, would result in a brush holder assembly which would project beyond the outline of the motor casing and would thus interfere with the free flow of dust-laden air about the motor.

To conveniently move the cleaner over the surface undergoing cleaning, a handle indicated in its entirety as at 100 is provided (Fig. 10). The handle comprises a tube having the upper end thereof bent to provide a hand grip portion and the lower end thereof secured to a pivoting bracket 101. The grip portion of the handle is preferably covered with a rubber sleeve 102 which is apertured at its upper side to expose a switch 103. The lower end of the tube is secured to the bracket 101 by a transverse locking screw 104. The strain relief 105 is provided for the electric cord 106 and one wire such as 107 of the cord is connected through the switch 103. The cord 106 emerges from the handle at the lower end thereof and leads therefrom to the motor. The bracket 101 is pivotally connected by pin 108 to a mounting member 109 on the cleaner body having spaced parallel ears 110.

The handle in its entirety is normally urged toward a vertical position as shown in Figure 11 by a coil spring 111 which is wrapped about the pin 108. One end of the coil spring such as indicated at 112 bears against the base of a U-shaped mounting member 109 and the other end of the coil spring such as 113 bears against the lower, forward wall of the pivot bracket 101. The upper edges of the ears 110 are notched as at 114, 115 and 116 to cooperate with a pivoted latch member 117 which is pivotally carried by the bracket 101 as at 118 and is urged into latch engagement by a coil spring 119 inserted between the forward wall of the bracket and the latch. The latch may be released from a latched position in notch 114, 115 or 116 by means of a latch rod and trigger arrangement 120-121. The trigger 121 is pivoted as at 122 near the grip portion of the handle and an upward pull on the trigger 121 is effective to swing the latch 117 about its pivot against the tension imposed thereon by spring 119. Other means for moving the latch may be employed. For instance, the pin 108 may project beyond the side walls of the bracket 101 and the extended portion provided with a foot-operated lever.

The above-described pivoting and latching arrangement for the handle provides that when the handle is swung to its vertical position, the

cleaner may be conveniently carried about without swinging with respect to its pivotal mounting. When, however, the cleaner is to be pushed about the floor, the latch 117 is released by means of the trigger 121 so that the handle may assume an inclined position such as shown in Figure 10 convenient for the operator. The notch 114 provides that the handle may be swung to a position substantially parallel to the surface being cleaned and thus the cleaner may be moved beneath a bed, chair or the like, to clean a surface thereunder. The coil spring 111 is preferably selected so that it substantially counterbalances the weight of the handle and thus facilitates the manipulation of the handle to and from its position of use.

The nozzle portion of the cleaner is provided on its front and side walls with a resilient bumper 123, to prevent the marring of furniture by contact with the cleaner. The casting 4 which overhangs the belt pulley on the motor and the light is also provided with a strip of rubber 121 which is secured thereto in alignment with a strip of rubber 122 on the casting 2.

Although I have shown and described one form of my invention in considerable detail, it will be appreciated that those skilled in the art may effect numerous modifications thereof without departing from the scope of the invention as defined in the following claims.

I claim:

1. A suction cleaner comprising a lower body portion provided with supporting wheels at its underside, a nozzle integrally formed in said lower body portion, an upper body portion secured to the lower body portion and forming therewith a passageway, a motor and fan unit mounted within said shell and contacting the lower wall thereof, whereby air moving through said passageway around the motor cools the motor, apertures formed in the wall of said shell and in the wall of the motor casing in the contact area between the motor and shell, means within the motor casing to induce a flow of ventilating air in through one of said apertures and out through another of said apertures.

2. A suction cleaner comprising an integrally-formed nozzle and body portion, a cover for said body portion, forming therewith an elongated shell, a motor having a sealed casing mounted within said shell on the lower wall thereof, a pair of spaced, aligned apertures formed in said motor casing and in said shell in said lower wall portion, a fan within said motor casing adapted to draw motor ventilating air through one of said apertures and exhaust the air through the other of said apertures.

3. A suction cleaner comprising a dust bag, a body having an integrally-formed floor nozzle section and an elongated, cup-like recess in said body rearwardly of said nozzle, a similarly-shaped, elongated, cup-like cover arranged over said recess and forming therewith an elongated shell adapted to form a passageway extending longitudinally of the body leading from the nozzle to said dust bag carried at the rear of the cleaner body, a horizontally-arranged motor secured to the lower wall of said recess, a suction-producing fan mounted on said motor within said recess, a sealed casing for said motor, a ventilating fan within said sealed casing, apertures in said casing and in the wall of the shell beneath the casing, whereby said motor is cooled by air moving in the passageway exterior of the casing and by air moving through said apertures to the interior of said casing.

4. A suction cleaner body comprising a main casting including an integrally-formed nozzle and motor and fan unit housing, a cover casting over said housing and forming therewith an elongated shell to enclose a motor and fan unit, a motor casing mounted on a flattened portion of said shell and spaced from the major portion of the wall thereof to provide an air passageway leading from the nozzle and around said motor casing, said casing sealed with respect to said air passageway and provided with openings aligned with openings in the shell, leading to the exterior of said shell, whereby said motor may be cooled by ventilating air drawn from the exterior of the shell and by air moving through said passageway.

PAUL E. FRANTZ.
